LAWN CHAIR

Armitt Brown, Mount Desert, Maine

Application March 24, 1934, Serial No. 717,236

2 Claims. (Cl. 155—30)

This invention relates to chairs and particularly to chairs designed for use on lawns or in gardens.

The general object of the invention is to provide a chair which is comfortable, which is easily moved without the necessity of bodily lifting the chair, which will remain stationary in any position in which it is placed even on a slant and which will not harm or destroy the turf or mar the appearance of a lawn.

A further object of the invention is to provide a chair of this character having forward legs and rear wheels, the wheels being so disposed that the chair may be readily tilted backward off its front legs so as to permit the chair to be rolled, the front legs acting, when the chair is again disposed in a horizontal position, to hold the chair firmly against movement even though the chair be placed on a comparatively steep slope.

Other objects will appear in the course of the following description.

My invention is illustrated in the accompanying drawings, wherein:

Figure 1 is a side elevation of a chair constructed in accordance with my invention, the foot rest being disengaged from the chair and placed in one of its foot supported positions;

Figure 2 is a top plan view of the structure shown in Figure 1;

Figure 3 is a front elevation of the chair shown in Figure 1;

Figure 4 is a plan view of the sub-structure of the chair below the seat, the front uprights of the chair being in section;

Figure 5 is a fragmentary cross section through the transverse member 11 on the line 5—5 of Figure 4;

Figure 6 is a rear elevation of the rear brace.

Referring to the drawings, it will be seen that the chair is mainly supported by two front vertically extending legs 10 shown in section in Figure 4 and by a rear transverse member 11 which is recessed at 12 to receive the axle 13, this axle being preferably of metal and being held to the member 11 in any suitable manner. This axle 13 carries upon it the wheels 14 which may be of any suitable character and are shown as disk wheels with rubber tires.

Disposed in notches in the rear faces of the legs 10 are the notched ends 15^a of a transverse element 15 and the notched ends 16^a of a transverse element 16. The middle of the transverse element 15 is formed with a notch 17, as shown in Figure 3 while the transverse element 16 is formed with two notches 18 as shown in Figures

3 and 4. The transverse member 11 is formed upon its under face with a notch 19 as shown in Fig. 6 and with two end recesses or notches 20. Fitting into the notch 17 in the transverse rail 15 is a longitudinally extending brace 21 which at its rear end is notched to fit within the notch 19 as shown in Figure 5 with the tongue of this member 21 disposed just above the axle 13. Disposed within the notches 18 are two downwardly and rearwardly extending braces 22 which engage notches 18 at their forward ends and at their rear ends engage with the notches 20 in rail 11.

The members 15 and 21 and 11 and 21 and 16 and 22 and 11 and 22 may be connected to each other by screws, nails or other suitable connecting devices in a manner which will be obvious, screws being preferably used.

Extending across the braces 22 forward of the transverse member 11 is a transverse brace 23 notched at its ends as at 24 to fit over the rails 22 and bolted to these rails by bolts 25. It will be seen that this transverse member 23 assists in holding these rails 22 in proper spaced relation to each other and bracing the rails 22.

Attached to the legs 10 just forward of the junction of rails 22 with these legs is a fascia 26 as shown in Figures 1 and 3, which fascia is relatively wide and held in place by screws, nails or the like extending into the legs 10.

Extending upward and rearward is a back formed of a medially disposed panel 27 and two laterally disposed planks or strips 28 having their edges spaced from the edges of the panel 27. These three sections 27 and 28 are held together by transverse braces 29 and 30. This back is preferably disposed at an angle of about 98° with relation to the braces 22. The lower end of the back rests upon these braces 22 and the lower end of the back may be attached to the transverse member 23 by screws or otherwise.

Seat slats 31 are disposed in spaced relation upon the members 22 and held thereto by screws or other fastening devices, these seat slats extending transversely of the chair, the forward-most slat engaging against the fascia 26.

Arm rests 32 are provided which are relatively wide at their forward ends but narrower at their rear ends, these arm rests being attached to the upper ends of the uprights 10 by screws or other suitable means and resting upon and being attached to laterally disposed brackets 33 attached to and projecting laterally from the vertical members 10.

The lateral members 28 of the back are slotted

at 34 to receive the inner edges of these arm rests and these arm rests at their rear ends are connected to the transverse brace 30 as by screws, nails or the like so that these arm rests act to brace the rearwardly and upwardly extending back against rearward movement.

It will be seen that the back extends upward and rearward quite a little bit beyond the axle so as to give sufficient leverage as to permit a person to readily tilt the chair back on its wheels, lifting the front legs 10 from the ground and thus permit the chair to be easily shifted forward or rearward on the wheels alone. The back, as before stated, has preferably an angle of 98° with reference to the seat and the seat has preferably an angle of 73° with relation to the front legs as these angles have been found to give particular comfort to a seated person. The upper end of the back is provided with a hand hold 35 and the arm rests are also provided with hand holds 32^a, permitting the chair to be readily handled. By lifting up on the arms, the front legs of the chair may be raised sufficiently from the ground to permit the chair to be readily wheeled forward.

The arm rests 32 are particularly wide so as to function not only as arm rests but shelves upon which books, tea things and other matters may be placed.

The chair is also provided with a foot rest designated 36 and shown in Figures 1 and 2 comprising the end members 37 which are rounded at their lower ends as at 38 so as to form rockers, a transverse board or brace 39 attached to the end members in any suitable manner, and a transverse cleat 40 nailed, bolted or otherwise attached to the foot rest 36 and nailed, screwed or bolted to the transverse member 39. This foot rest 36 is preferably narrowed toward its rear end and provided with a hand hold 41. The foot rest when not in use is disposed, as shown in dotted lines in Figure 1, with its lateral legs or members 37 overlapping the ends of the legs 10 with the board resting upon the longitudinal rail 21 or the foot rest may be disposed as shown in Figure 1 with the rear end of the foot rest lying upon the ground, the foot rest then being inclined upward and forward or the foot rest may be disposed at an inclination upward and rearward with its upper end resting upon the seat and the legs extending upward and forward or with the rear end of the foot rest disposed upon the transverse brace 15 and the foot rest in a horizontal position.

In my construction, by providing forward legs of the proper cross sectional area and rear wheels disposed, as shown, the chair when resting with its front legs upon the ground is held by these front legs in any set position so that it will not roll even when the slope is as much as 45°. At the same time by depressing the back of the chair or raising upward on the arm rests, the chair may be readily tilted to lift the front legs off of the ground and permit the chair to be rolled to any desired position.

The construction of the chair is much lighter than the usual wooden garden chair and the rear wheels permit it to be moved with such ease that it never remains long enough in one spot to injure the surface upon which it rests nor for the same reason will the grass immediately in front of the chair be injured by the occupant's feet. Furthermore, of course, where the foot rest is used, the feet of the occupant will not rest upon the grass.

The fact that the chair does not injure the

grass of a lawn may seem unimportant, but in reality it is particularly important for a lawn or garden chair. Chairs of this general character are so clumsy that they very rarely, if ever, are moved, and as a consequence, injure the grass of the lawn wherever they are placed. In view of the fact that the slats 31 are spaced from the back 28, as well as from each other, no water will accumulate upon the seat but the water will fall through and thus the seat will readily dry off after a rain.

The angles at which the back and seat meet each other have been carefully calculated to provide maximum comfort.

It will be noted that the seat slats run transversely of the chair instead of longitudinally as they do in many garden chairs which longitudinal direction of the seat slats is most uncomfortable.

It will be noted that this chair is particularly designed for simplicity and relative lightness, the frame consisting, omitting the slats, of seven pieces of exactly the same dimensions in width and thickness but varying only in length and one other piece, namely the cross piece 11.

The wood is preferably either cypress or soft pine so as to be light in weight and offers resistance to the weather at the same time. The foot piece may be either left to rest upon the ground, as shown in Figure 1, or by pressing with the feet against the front board 39, the foot rest may be tilted upward at its rear end against the calves of the legs and the weight of the legs counter-balancing the pressure of the feet, the foot rest may remain fixed at any angle which may be comfortable to the user.

I claim:—

1. A chair comprising front legs, upper and lower transverse braces connecting said legs, a rear transverse member, wheels carried thereby, a lower rail connecting the lower brace to said transverse member, a pair of upper rails connected to the upper transverse brace and extending downward and rearward and engaged with said rear transverse member, the legs extending above said upper brace and the pair of rails, a transverse element attached to the rear ends of said pair of downwardly and rearwardly extending braces, a back attached to the transverse member and extending upward and rearward therefrom and at its upper end extending beyond a vertical plane intersecting the axis of said wheels, a transverse brace attached to said back, arm rests at their forward ends supported on and attached to the upper ends of the legs, the rear ends of the arm rests extending beyond the back and resting upon the transverse member, the back being slotted to receive the inner edges of said arm rests, brackets on the legs supporting said arm rests, and transverse spaced slats attached to the downwardly and rearwardly extending rails and constituting a seat.

2. A lawn chair including front legs, a lower brace and an upper brace notched into said legs and connecting the same, the upper brace being disposed below the upper ends of the legs, a rear transverse member having wheels at its ends, a single longitudinally extending rail connecting the lower brace with said transverse member, a pair of downwardly and rearwardly extending rails connecting the upper brace with said transverse member, a fascia plate attached to the legs and extending across the ends of the pair of rails, transversely extending spaced slats car-

ried upon said downwardly and rearwardly extending rails and constituting a seat, a transverse member mounted upon the rear ends of the rails rearward of the slats, a back having its lower end abutted against said transverse member and the pair of rails and extending upward and rearward to a point above and rearward of a vertical plane passing through the axis of the wheels, a transverse brace carried upon the rear face of the

back on a level with the upper end of the legs, laterally extending brackets mounted upon the legs, and arm rests carried by the upper ends of the legs and said brackets, the rear ends of the arm rests being supported by said transverse brace on the back, the back being slotted to receive the inner edges of the arm rests.

ARMITT BROWN.
